(57) **CLAIM**

The ornamental design for a golf related container, as shown and described.

DESCRIPTION

FIG. 1 is a perspective view of a golf related container; FIG. 2 is a right side elevational view thereof; FIG. 3 is a left side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a fragmentary cross-sectional view along line 8-8 of FIG. 7 in order to illustrate the contour; FIG. 9 is a perspective view of a second embodiment thereof; FIG. 10 is a right elevational view of a second embodiment thereof; FIG. 11 is a left side elevational view of a second embodiment thereof; FIG. 12 is a front elevational view of a second embodiment thereof; FIG. 13 is a rear elevational view of a second embodiment thereof; FIG. 14 is a top plan view of a second embodiment thereof; and, FIG. 15 is a bottom plan view of a second embodiment thereof.

The dash-dash broken lines shown in the drawing illustrate portions of the golf related container that form no part of the claimed design.

The dash-dot broken lines in FIG. 8 depict the boundary of the fragmentary cross-section and form no part of the claimed design.

The dash-dot broken line shown in FIG. 7 indicates a section line that forms no part of the claimed design.

1 Claim, 15 Drawing Sheets
